UNITED STATES - PATENT - OFFICE.

HENRY R. MYERS, OF COVINGTON, KENTUCKY.

LIQUID-CONTAINER.

SPECIFICATION forming part of Letters Patent No. 698,309, dated April 22, 1902.

Application filed January 20, 1902. Serial No. 90,420. (No model.)

To all whom it may concern:

Be it known that I, HENRY R. MYERS, a citizen of the United States, residing at Covington, in the county of Kenton and State of Kentucky, have invented certain new and useful Improvements in Liquid-Containers; and I do declare the following to be a full, clear, and exact description of the invention, such as will enable others skilled in the art to which it appertains to make and use the same.

The invention relates to liquid-containers, and more particularly to that class in which a surrounding protective jacket is employed.

The object of the invention is to provide a liquid-container which shall be simple of construction, durable in use, comparatively inexpensive of production, and one in which the liquid may be visually inspected for the purpose of ascertaining before sealing (or, if sealed, before decanting) whether or not there are any dregs or sediment in the bottom of the container.

With this and other objects in view the invention consists of certain novel features of construction, combination, and arrangement of parts, which will be hereinafter more fully described, and particularly pointed out in the appended claim.

In the accompanying drawings, Figure 1 is a perspective view of my improved liquid-container, and Fig. 2 is a vertical longitudinal sectional view.

Referring to the drawings, 1 denotes the vessel of the container, preferably made of glass and of any suitable shape and dimension.

2 denotes the usual protective jacket, preferably made of wood veneer, entirely surrounding the sides of the vessel.

3 denotes the upper metallic band encircling the upper end of the jacket, and 4 denotes the lower metallic band encircling the lower end of the jacket. The upper band at diametrically opposite points has stamped out therefrom semicircular ears or lugs 5, with which are engaged the hooked ends of the handle or bail 6.

7 denotes vertically-disposed strips the upper ends of which extend between the upper band and the jacket and are hooked over and engaged with the upper edge of the upper band. The lower ends of these strips pass

between the lower band and the jacket and are riveted to the lower band, and thence pass under the lower edge of the jacket and an inner supporting-ring 8, secured to the lower end of the jacket to support the bottom of the vessel. After passing under the lower edges of the jacket and inner supporting-ring the strips pass upwardly and lie close against the inner sides of the inner supporting-ring, over the upper edges thereof, and thence upwardly against the inner sides of the jacket, as shown more particularly in Fig. 2. The lower extremities of these strips are thus confined between the exterior wall of the glass vessel and interior wall of the closely-fitting jacket, and thus serve to additionally support the inner supporting-ring 8, secured to the lower end of the jacket.

It will be noticed that the bottom of the vessel is supported entirely clear of the floor by this inner supporting-ring, and thus lessens the liability of breakage due to sudden shocks. It will also be noticed that by providing no cover for the bottom of the vessel the contents of the vessel may be readily inspected by holding it up to the light, and thus any impurities, sediment, or dregs be discovered before shipment of the package.

From the foregoing description, taken in connection with the accompanying drawings, the construction, mode of operation, and advantages of the invention will be readily understood without requiring an extended explanation.

Various changes in the form, proportion, and details of construction may be made within the scope of the invention without departing from the spirit or sacrificing any of the advantages thereof.

Having thus described my invention, what I claim, and desire to secure by Letters Patent, is—

A liquid-container, comprising a vessel, a jacket surrounding the vessel and having its lower end projecting below the bottom of the vessel, a supporting-ring secured to the inner wall of the jacket and adapted to support the vessel at a point above the lower end of the jacket, bands secured to the exterior of the jacket at its upper and lower ends, vertically-disposed strips connecting the said bands, said strips having their lower ends bent under

the lower edges of the jacket and the inner supporting-ring and thence upwardly against the inner face of the supporting-ring, thence over the upper edge of the supporting-ring 5 and thence upwardly parallel with the jacket and confined between said jacket and the vessel, substantially as set forth.

In testimony whereof I have hereunto set my hand in presence of two subscribing witnesses.

HENRY R. MYERS.
